UNITED STATES PATENT OFFICE.

HENRY J. SCHULTE, OF FULLERTON, CALIFORNIA.

ENGINE-STARTER.

1,220,692.

Specification of Letters Patent. Patented Mar. 27, 1917.

Application filed December 16, 1915. Serial No. 67,153.

To all whom it may concern:

Be it known that I, HENRY J. SCHULTE, a citizen of the United States, residing at Fullerton, in the county of Orange and State 5 of California, have invented new and useful Improvements in Engine-Starters, of which the following is a specification.

This invention relates to an engine starter and particularly pertains to a spring actuated mechanism for rotating the crank shaft 10 of the gas engine in starting same.

It is the object of this invention to provide a spring operating mechanism for starting gas engines which is adapted to be 15 reenergized by means of the engine.

Another object is to provide a spring starter for engines adapted to be energized by the engine having means for automatically cutting out reenergizing connection 20 with the engine shaft when the actuating spring has been wound to a predetermined tension.

Another object is to provide a simple and effective means for throwing the spring into 25 operative connection with the engine shaft to rotate the latter.

A further object is to provide an actuating spring of the helical type so formed as to return upon itself to obtain a considerable 30 spring length within a small space.

Other objects will appear hereinafter.

The invention is illustrated in the accompanying drawings in which:

Figure 1 is a plan view illustrating the invention as applied.

Fig. 2 is a view of same in side elevation.

Fig. 3 is an enlarged vertical section as seen on the line 3-3 of Fig. 1 with parts broken away, showing the actuating spring 40 and its connections.

Fig. 4 is an enlarged detail section as seen on the line 4-4 of Fig. 1 showing the clutch connections of the engine drive crank shaft.

Fig. 5 is a detail section and elevation as 45 seen on the line 5-5 of Fig. 4 in the direction indicated by the arrows, showing the spring winding clutch.

Fig. 6 is a detail section as seen on the line 6-6 of Fig. 4 in the direction indicated 50 by the arrows, showing the crank shaft driving clutch.

Fig. 7 is a detail section on the line 7-7 of Fig. 3 as seen in the direction indicated by the arrows, showing the manually controlled operating brake whereby the spring 55

is thrown in and out of driving connection with the engine shaft.

More specifically, 10 indicates a crank or drive shaft of the gas engine such as is employed in propelling automobiles and the 60 like, and carried by a frame 11 of any suitable construction.

In carrying out the invention, the outer end of the crank shaft 10 is equipped with a pair of clutches 12 and 13, as particularly 65 shown in Figs. 4, 5 and 6. The clutch 12 embodies an internal clutch member 14 keyed on the shaft 10, and an external clutch member 15 revolvably mounted and held against longitudinal movement in relation to the 70 shaft 10. The clutch member 14 is formed in the shape of a disk having a series of tapered depressions 16 on its peripheral edge in which engaging rollers 17 are mounted. The rollers 17 form a means of connection 75 between the clutch member 14 and an annular flange on the member 15 encompassing the disk portion of the clutch, as particularly shown in Fig. 6, in a manner as will be later described. 80

The clutch 13 embodies a clutch member 18 mounted to rotate and held against longitudinal movement in relation to the shaft 10, and a slidably clutch member 19 keyed on the shaft. The clutch member 19 is formed 85 with a tapered annular face 20 adapted to be thrown in and out of frictional engagement with a tapered flange 21 on the clutch member 18, as will be later described. The clutch members 15 and 18 are formed with 90 sprocket teeth 22 and 23 which are engaged by endless sprocket chains 24 and 25, respectively.

Conveniently mounted on the frame 11 and supported in suitable bearings is a shaft 95 26 extending parallel to the shaft 10. Revolvably mounted on the shaft 10 and held against longitudinal movement thereon is a sprocket wheel 27 formed with a brake drum 28 on one side thereof, around which a brake band 29 extends; the brake band 29 being normally in engagement with the drum 28 to hold the sprocket wheel 27 against rotation. The sprocket wheel 27 is engaged by the sprocket chain 24 leading 100 from the sprockets on the clutch 12, as shown in Fig. 1. Keyed on the shaft 26 is a sprocket wheel 30 around which the sprocket chain 25 leading from the clutch 13 passes, as shown in Fig. 1. Wound 110

around the shaft 26 is a double helical spring 31. One end of the outermost portion of the spring connects with the sprocket wheel 27, as indicated at 33 in Fig. 3. The 5 opposite end of the outer coil connects with and is formed in continuation of the inner coil, the opposite end of which is rigidly connected at 34 to a collar 35 rigidly secured to the shaft 26 adjacent the sprocket 10. 27. As a means for preventing rotation of the sprocket 30 by the spring 31, a pawl 36 is mounted on a stationary bearing or bracket 37 and arranged to normally engage sprocket teeth 38 formed on the hub 15 of the sprocket 30.

The clutch member 20 is controlled by a lever 39 having a yoke 40 engaging an annular groove 41 on the clutch member. The lever 39 is pivoted at 42 on a bracket 20 or suitable support 43 and has its outer end connected to a reciprocating rod 44 leading to any convenient point of operation and which rod is adapted to be advanced or retracted in any desired manner, to rock the lever 39.

The brake 29 controlling the spring actuated sprocket 27 is controlled by means of a reciprocating bar 45 which leads from any suitable actuating mechanism and connects with a bell crank lever 46 connecting with an arm 47 pivoted at 48 and connected to the brake band 29 as particularly shown in Fig. 7.

The operation of the parts previously described is as follows:

Assuming that the spring 31 is under tension and that it is desired to rotate the shaft 10 thereby, on advancing the bar 45 to release the brake band 29, the spring 31 40 will unwind and in so doing will rotate the sprocket 27, chain 24, and the clutch member 15; the latter being turned in the direction indicated by the arrow *a* in Fig. 6. The flanged portion of the clutch member 15 45 will engage and advance the rollers 17 in the depressions 16 toward the convergent portions thereof, thus wedging the rollers, causing them to engage the clutch member 15 so that the pull of the spring 31 will be 50 transmitted through the clutch 12 to rotate the shaft 10. When the engine is started, the shaft will continue rotating in the direction of the arrow *a* at a speed greater than that of the clutch member 15, the 55 movement of which may be stopped by retracting the bar 45 to tighten the brake band 29. The rotation of the shaft 10 will then cause the rollers 17 to be retracted into the enlarged portion of the depressions 16 60 out of engagement with the clutch member 15. The latter will then remain stationary and the clutch member 14 will revolve therein.

When it is desired to reenergize the spring 65 31, the rod 44 is operated to rock the lever

39 and move the tapered clutch member 20 into frictional engagement with the clutch member 18, which will then rotate and operate through the sprocket chain 25 to revolve the sprocket 30 and the shaft 26; the 70 shaft 26 rotating in such direction as to wind the spring 31. By taking off the driving power of the spring from one end thereof and winding it from its opposite end, the direction of rotation to turn the 75 shaft 10 in starting the engine and in rotating the shaft 26 from the shaft 10 will be the same.

Means are provided for automatically cutting out the clutch 18 when the spring 31 80 has been sufficiently energized. This means is here shown as consisting of a slideable member 49 mounted on the shaft 26 adjacent the outer end of the spring 31; the member 49 being adapted to operate a trip 85 lever 50 to which a connecting rod 51 leading from the outer end of the lever 39 is attached. On tightening the spring 31 and contracting the coils thereof, this spring is lengthened so as to cause the member 90 49 to advance and operate the trip lever 50 which in turn will actuate the lever 39 through the rod 51 in such manner as to throw the clutch member 20 out of engagement with the clutch member 18; the rod 95 44 by which the clutch had previously been thrown in operation having been released. This arrangement prevents the spring 31 from being over-wound.

As a means for permitting the spring to 100 be re-wound independent of the engine shaft 10, the shaft 26 is formed with a squared outer end to receive a crank 52 as shown in Fig. 2. Likewise the shaft 10 is adapted to receive a crank 53 by means of 105 which it may be rotated to start the engine independent of the starting device should occasion so require.

What I claim is:

1. In an engine starter, an engine shaft, a spring for rotating said engine shaft, means driven by the engine shaft for energizing said spring, means whereby the spring may elongate as energized, and automatic means operated by the elongating action of said spring to disconnect the spring energizing means from the engine shaft. 110

2. In an engine starter, a rotatable shaft, a spring coiled about said shaft and secured at one end thereto, a rotatable element loosely mounted on said shaft and connected to the other end of said spring, an engine shaft, disengageable means connecting the rotatable element to said engine shaft, disengageable means rotatably connecting the engine shaft to the first-mentioned shaft to energize the spring, means whereby the spring may be elongated as energized, and means operated by the elongation of said spring when being energized 115 120 125 130

to automatically throw out of engagement said last named disengageable means.

3. In an engine starter, the combination with the engine drive shaft, of a clutch member keyed to said shaft, a sprocket adapted to be engaged by said clutch member when rotated in the same direction as the engine shaft, a second shaft parallel to said engine shaft, a sprocket wheel loosely mounted

10 upon said second shaft, transmission means connecting said sprocket wheel and the first-named sprocket, a spring wound around said second shaft and having one end connected thereto and its other end connected to said

15 loosely mounted sprocket wheel, a brake-band engaging said wheel to hold it against rotation by said spring, a fixed sprocket wheel secured at the outer end of said second-named shaft, a loose sprocket wheel

20 mounted upon the outer end of the engine shaft, clutch means for locking said loose sprocket wheel to the engine shaft, transmission means for producing simultaneous rotation of the sprocket wheels at the ends

25 of the engine and second-named shafts, and automatically operable means whereby said spring may act to disengage the loose wheel mounted upon the end of the engine shaft from the engine shaft.

30 4. In an engine starter, the combination with the engine drive shaft, of a clutch member keyed on said drive shaft, a loose rotary clutch member adapted to be disengageably connected with the first-named clutch mem-

35 ber, a second shaft, a loose wheel thereon, transmission connections between said wheel and the rotary clutch member, a spring wound around said shaft having one end connected thereto and its opposite end at-

40 tached to the wheel, a brake-band normally engaging said wheel to hold same against rotation in opposition to the spring, a sec-
ond wheel keyed on said last-named shaft, a loose clutch member on the engine shaft
45 rotatably connected to said wheel, and means for engaging said clutch member with the engine shaft to rotate the second shaft and wind the spring thereon.

50 5. In an engine starter, the combination with the engine drive shaft, of a clutch member keyed on said drive shaft, a loose rotary clutch member adapted to be disengag-
eably connected with the first-named clutch member, a second shaft, a loose wheel

55 thereon, transmission connections between said wheel and the rotary clutch member, a spring wound around said shaft having one end connected thereto and its opposite end attached to the wheel, a brake band nor-
mally engaging said wheel to hold same

60 against rotation in opposition to the spring,

a second wheel keyed on said last-named shaft, a loose clutch member on the engine shaft rotatably connected to said wheel, means for engaging said clutch member with 65 the engine shaft to rotate the second shaft and wind the spring thereon, and means operable by said spring for automatically disconnecting said last-named clutch member when the spring has been wound to a 70 predetermined extent.

6. In an engine starter, a revoluble shaft, a loose wheel thereon, a helical spring wound around said shaft and returned upon itself, having one end secured to said wheel and its 75 other end engaging the shaft, means for holding the shaft against rotation in opposition to the spring, means for holding the wheel against rotation in opposition to the spring, means connected to said wheel for 80 driving an engine shaft by said spring, means operable by the engine shaft for rotating the first-named shaft to energize the spring, means whereby the spring may elongate as energized, and means controlled by 85 the spring as it elongates to automatically throw out its energizing means.

7. In an engine starter, a revoluble shaft, a loose wheel on said shaft, a helical spring wound on said shaft and returned upon it- 90 self with one end connected to the shaft and its other end connected to the wheel, means for holding said wheel against rotation, means for holding the shaft against rotation in one direction in opposition to the spring, 95 means for rotating said shaft from an engine shaft, a clutch controlling said means normally disengaged, means for manually throwing in said clutch, and means controlled by said spring for automatically 100 throwing out the clutch when the spring has been wound to a predetermined extent.

8. In an engine starter, a revoluble shaft, a loose wheel on said shaft, a helical spring wound on said shaft and returned upon it- 105 self with one end connected to the shaft and its other end connected to the wheel, means for holding said wheel against rotation, means for holding the shaft against rotation in one direction in opposition to the spring, 110 means for rotating said shaft from an engine shaft, a clutch controlling said means normally disengaged, means for manually throwing in said clutch, a trip lever arranged adjacent the doubled end of said 115 spring adapted to be engaged by the latter on extension thereof, and means operable by said trip lever for automatically throwing out said clutch.

In testimony whereof I have signed my 120 name to this specification.

HENRY J. SCHULTE.
